UNITED STATES PATENT OFFICE

123,948

DESIGN FOR A SHOOTING RANGE CABINET

Frank E. Shailor, Sr., Detroit, Mich., assignor to Tru-Shot Corporation, Detroit, Mich., a corporation of Michigan

Application July 28, 1938, Serial No. 78,789

Term of patent 3½ years

To all whom it may concern:

Be it known that I, Frank E. Shailor, Sr., a citizen of the United States of America and residing at Detroit, in the county of Wayne and State of Michigan, have invented a new, original, and ornamental Design for a Shooting Range Cabinet, of which the following is a specification, reference being made to the accompanying drawings, forming part thereof.

Fig. 1 is a front view of a shooting range cabinet showing my new design.

Fig. 2 is a vertical side section of the shooting range cabinet.

Fig. 3 is a perspective view of the shooting range cabinet showing a portion of the interior.

The dominant features of my design are shown in solid black lines in the drawings.

I claim:

The ornamental design for a shooting range cabinet, substantially as shown and described.

FRANK E. SHAILOR, SR.
